- (73) Assignee: **Chrysanthemum Breeders Association N.V. (NL)**
- (*) Notice: Subject to any disclaimer, the term of this patent is extended or adjusted under 35 U.S.C. 154(b) by 75 days.
- (21) Appl. No.: **11/020,258**
- (22) Filed: **Dec. 27, 2004**

1**BACKGROUND OF THE INVENTION**

'Homer' is a product of a breeding and selection program for outdoor pot mums (garden mums) which had the objective of creating new *chrysanthemum* cultivars with a decorative type flower, a natural season flower date around August 16–23; blooming for a period of 6 weeks. The new plant of the present invention comprises a new and distinct cultivar of *Chrysanthemum* plant 'Homer' is a seedling resulting from a crossing program, which was set up by a previous breeder, and which records are unknown to the inventor. The new and distinct cultivar was discovered and selected as a flowering plant by Mark Roland Boeder on a cultivated field in Rijsenhout, The Netherlands in 2001. The first act of asexual production of 'Homer' was accomplished when vegetative cuttings were taken from the initial selection in 2001 in a controlled environment in Rijsenhout, The Netherlands, and propagated further at this location. The new cultivar has been found to retain its distinctive characteristics through successive propagations.

BRIEF DESCRIPTION OF THE DRAWINGS

The present invention of a new and distinct variety of *chrysanthemum* is shown in the accompanying drawings, the color being as nearly true as possible with color photographs of this type.

FIG. 1 shows a plant of the cultivar in full bloom.

FIG. 2 shows the various stages of bloom of the new cultivar.

FIG. 3 shows the foliage of the new cultivar.

DESCRIPTION OF THE INVENTION

This new variety of *chrysanthemum* is of the botanical classification *Chrysanthemum morifolium* L. The observations and measurements were gathered from plants grown out door in Rijsenhout, The Netherlands under natural day length and temperature and planted week 24 in 2004. The natural blooming date of this crop was August 16–23 (week 34). The average height of the plants was 25 cms. No growth retardants were used. No tests were done on disease or insect resistance or susceptibility. No tests were done on cold or

ABSTRACT

A *chrysanthemum* plant named 'Homer' characterized by its medium sized blooms with orange ray florets and good branching natural season flower date August 16–23; blooming for a period of 6 weeks.

3 Drawing Sheets**2**

drought tolerance. This new variety produces medium sized orange blooms flowering for a period of 6 weeks.

From the cultivars known to inventor the most similar existing cultivars in comparison to 'Homer' are 'Beryl' (U.S. Plant Pat. No. 15,416) and 'Hector' (U.S. Plant Pat. No. 15,404). When 'Homer', 'Beryl' and 'Hector' are being compared the following similarities and differences are noticed: All three varieties have medium sized decorative type orange blooms. The differences of 'Homer' and 'Beryl' and 'Hector' are (1) Number of ray-florets. 'Homer' has a higher number of ray-florets than 'Beryl' and 'Hector'. (2) Size of bloom. Because of this high number in 'Homer', its blooms are large and more spherical shaped than those in 'Beryl' and 'Hector'.

The following is a description of the plant and characteristics that distinguish 'Homer' as a new and distinct variety. The color designations are taken from the plant itself. Accordingly, any discrepancies between the color designations and the colors depicted in the photographs are due to photographic tolerances. The color chart used in this description is: The Royal Horticultural Society Colour Chart, edition 1995.

TABLE 1**Botanical Description of *chrysanthemum* plant 'Homer'**

<u>Bud</u>	
Size	Small; cross-section 0.5 cm, height 0.5 cm
Outside Color	Yellow-green 145D
Involucral bracts	2 rows, length 7 mm, width 3 mm
Involucral bracts among disc-florets	Not present
Involucral bracts color	Green 138A–138B
<u>Bloom</u>	
Type	Decorative
Height	2 cm
Size	Medium
Fully Expanded	5.5 cm
Peduncle length	6–7 cm
Peduncle color	Green 139C
Number of blooms per branch	Approx. 6 blooms per branch
Performance on the plant	6 weeks

TABLE 1-continued

Botanical Description of <i>chrysanthemum</i> plant 'HOMER'	
Seeds	Produced in small quantities, ovate grey-brown 199A, 1½ mm in length.
Fragrance	Typical <i>chrysanthemum</i> , slightly
<u>Color</u>	
Center of the flower	Immature Greyed-orange 171B
Color of upper surface of the ray-florets	Mature Greyed-orange 168B
Color of the lower surface of the ray-florets	Yellow-orange 17D overlain with Greyed-orange 167C
Tonality from Distance	Greyed-orange 164C overlain with Greyed-orange 167C
Discoloration to color	A garden mum with orange flowers
<u>Ray florets</u>	
Texture	Greyed-yellow 162B with
Number	Greyed-orange 164B
Cross-section	
Longitudinal axis of majority	
Length of corolla tube	
Ray-floret margin	Upper and under side smooth
Ray-floret length	280–300
Ray-floret width	Flat
Ratio length/width	Straight
Shape of tip	0.5 cm
Disc florets	Entire
<u>Receptacle shape</u>	2.5 cm
<u>Reproductive Organs</u>	0.6 cm
Stamen	Medium
Styles	Dentate
Style color	Absent
Style Length	Thickness
Stigma color	Yellow 13A
Stigma Width	4 mm
Ovaries	Yellow-green 144A
<u>Plant</u>	1 mm
Form	Enclosed in calyx
Growth habit	
Growth rate	Grown as a spray type potmum, outdoor mounded and round
Height	Spherical and spreading
Width	Medium
Stem Color	30 cm
Stem Strength	35 cm
Stem Brittleness	Green 138B with streaks of Greyed-red 182B
Stem Anthocyanin Coloration	Medium
Internode length	Brittle
Length of lateral branch	Present

TABLE 1-continued

Botanical Description of <i>chrysanthemum</i> plant 'HOMER'	
Lateral branch color	Green 138B–138C
Lateral branch, attachment	Weak
Branching (average number of lateral branches)	Good with 8–10 breaks after pinching
Natural season blooming date	August 16–23
<u>Foliation</u>	
Leaf color	Upper side Green 138A
Color midvein	Lower side Green 138B
Size	Upper side Green 139D
Quantity (number per lateral branch)	Lower side Yellow-green 148D
Shape	Medium; length 4–6 cm, width 2.5–4 cm
Texture upper side	20
Texture under side	Obovate
Venation arrangement	Glabrous
Shape of the margin	Pubescent
Shape of Base or Sinus Between Lateral Lobes	Palmate
Margin of Sinus Between Lateral Lobes	Serrated
Shape of Base	Rounded
Apex	Diverging
Petiole length	Acute-obtuse
Petiole color	Mucronulate

TABLE 2

Differences with the comparison varieties			
	'Homer'	'Beryl'	'Hector'
Bloom type	Decorative	Decorative	Decorative
Color upper side ray-florets	Yellow-orange 17D and Greyed-orange 167C	Orange 26C	Orange-red 34C
Number of ray-florets	280–300	250	250
Size of bloom	5.5 cm	4.5 cm	5.5. cm

I claim:

1. A new and distinct variety of *chrysanthemum* plant as described and illustrated.
